UNITED STATES PATENT OFFICE.

HENRY C. SEARLE, OF WEST ROXBURY, MASSACHUSETTS, ASSIGNOR TO UNITED SHOE MACHINERY CORPORATION, OF PATERSON, NEW JERSEY, A CORPORATION OF NEW JERSEY.

BUTTONHOLE-SEWING MACHINE.

1,388,313.

Specification of Letters Patent. Patented Aug. 23, 1921.

Application filed August 15, 1919. Serial No. 317,655.

To all whom it may concern:

Be it known that I, HENRY C. SEARLE, a citizen of the United States, residing at West Roxbury, in the county of Suffolk and 5 State of Massachusetts, have invented certain new and useful Improvements in Buttonhole-Sewing Machines; and I do hereby declare the following to be a full, clear, and exact description of the invention, such as 10 will enable others skilled in the art to which it appertains to make and use the same.

The invention relates particularly to that type of buttonhole sewing machine in which the stitch-forming mechanism comprises a 15 vertically reciprocating upper needle which penetrates the work a short distance from the buttonhole slit, a looper which takes a loop of the upper needle thread and holds it below the work in position for the passage 20 up therethrough of the under needle and an oscillating curved under needle which carries a loop of under thread up through the loop held by the looper and presents it in position for the passage down therethrough 25 of the upper needle.

Machines of this type are usually so constructed that the under needle passes up through the previously cut buttonhole slit throughout the sewing of the buttonhole so 30 that the needle is not subjected to the strains incident to piercing the work. Machines of this type may also be utilized in sewing buttonholes such as fly-bar buttonholes which require the under needle to penetrate the 35 work at the beginning and at the end of the sewing. In machines adapted for this class of work the needle may be subjected to strains which it is ill adapted to withstand and which may deflect it from the path required 40 for proper coöperation with the upper needle, particularly in sewing the final stitches of the seam which overlie the initial stitches so that the under needle must not only penetrate the work, but must also pass up through the initial end of the seam. Missed stitches and broken under needles 45 frequently result.

The present invention is designed to remedy the defect outlined above and to 50 render the operation of the stitch-forming mechanism certain and reliable. This is accomplished by providing the under needle with a surface which is arranged to uniformly press or crowd the point of the

needle inward or toward the axis of oscillation of the needle as it is forced through the work. Such a surface may conveniently be provided by locating the extremity of the needle point inside the axis of the needle so that the inclined surface from the point to 55 the outer side of the needle will have a greater rise and therefore a greater camming action or tendency to deflect the needle than the opposed surface on the inside of the needle. Whenever the needle thus formed penetrates the work its point will be pressed inward so that the pressure tending to deflect the needle will uniformly be in the same direction and in the direction which the 60 needle is best adapted to withstand and in which slight deflection of the needle will not materially affect its coöperation with the upper needle. Since any deflection which may result will always be in the same direction the proper preliminary adjustment of 65 the parts may readily be made to compensate for whatever deflection is likely to occur. The pressing inward of the point of the needle also insures a continued pressure 70 by the work on the outside of the needle during its passage through the work so that the work forms in effect a needle guide which uniformly bears upon the outside of the needle and supports and guides it in the proper path to coöperate with the upper 75 needle. 80

The invention is illustrated in the accompanying drawing in which Figure 1 is a sectional elevation of so much of a buttonhole sewing machine as is necessary to illustrate 85 the application of the invention thereto, and Fig. 2 is an enlarged view of the under needle.

In the drawing the invention is shown embodied in a buttonhole sewing machine 90 having the general construction and mode of operation of the machine shown and described in the patent to Hill, 1,063,880, June 3, 1913. The stitch-forming mechanism of this machine comprises a vertically recipro- 95 cating eye pointed upper needle 2, a looper 4 for taking a loop of upper thread and presenting it in position below the work for the passage up therethrough of the under needle, and an oscillating curved eye pointed 100 under needle 6 for carrying a loop of under thread up through the loop held by the looper and presenting it in position for the 105

passage down therethrough of the upper needle. These parts are mounted in rotary supports so that the stitch-forming mechanism may be rotated during the sewing of the buttonhole and are actuated by mechanisms fully described in said patent. The work is presented to the stitch-forming mechanism by a work clamp 8 which is mounted and actuated as in the machine of said patent. When the machine is designed to sew fly-bar buttonholes the cams which control the rotary movement of the stitch-forming mechanism and the movements of the work clamp lengthwise and transversely of the buttonhole are so shaped that the initial and final stitches of the seam are formed in the work in line with the bar end of the buttonhole slit, the final stitches overlying the initial stitches.

In embodying the preferred form of the invention in the above machine, the pointed end of the under needle is so formed that the point of the needle is inside the medial line or longitudinal axis of the needle. The inclined surface 10 extending from the point to the outside of the needle has therefore a greater rise than the inclined surface 12 extending from the point to the inner side of the needle, and the surface 10 will act by engagement with the work as the point of the needle penetrates the work to press the needle point inward toward the axis about which the needle oscillates. This will tend to bend or deflect the needle inward, and in case the stock is of a character to offer material resistance to the passage of the needle, will slightly deflect the needle so that the pressure on the outer side of the needle will be maintained during the upward stroke of the needle and will tend to guide and support it in its proper path of movement with relation to the upper needle. Any pressure or strain on the needle tending to deflect it is therefore uniformly in the same inward direction, and the parts may be adjusted to compensate for any variations in the deflection of the needle which are likely to occur. Outward strains which are likely to break the needle or to so deflect it that the upper needle will not pass through its loop are thus avoided and the proper coöperation of the stitch-forming devices insured.

While it is preferred to employ the specific construction shown and described, it will be understood that this is not essential to the broader features of the invention and

that the surface for pressing the needle inward may be otherwise located or formed.

What is claimed is:

1. A buttonhole sewing machine having, in combination, a vertically reciprocating upper needle, a looper for taking a loop of upper thread and presenting it in position below the work for the passage up therethrough of an under needle, an oscillating curved under needle for carrying a loop of under thread up through the loop held by the looper and presenting it in position for the passage down therethrough of the upper needle provided with a surface arranged to press the point of the needle inward toward its axis of oscillation by engagement with the work as the needle penetrates the work. 60

2. A buttonhole sewing machine having, in combination, a vertically reciprocating upper needle, a looper for taking a loop of upper thread and presenting it in position below the work for the passage up therethrough of an under needle, an oscillating curved under needle for carrying a loop of under thread up through the loop held by the looper and presenting it in position for the passage down therethrough of the upper needle provided with a point having its extremity between the inner side and the longitudinal axis of the needle. 75

3. A buttonhole sewing machine having, in combination, a vertically reciprocating upper needle, a looper for taking a loop of upper thread and presenting it into position below the work for passage therethrough of an under needle, an oscillating curved under needle for carrying a loop of under thread up through the loop held by the looper and presenting it in position for the passage down therethrough of the upper needle, and means for pressing the under needle inward during its passage through the work. 90

4. A curved eye pointed under needle for the overseam stitch-forming mechanism of a buttonhole sewing machine, having its point located between the inner side and the longitudinal axis of the needle. 105

5. A curved eye pointed under needle for the overseam stitch-forming mechanism of a buttonhole sewing machine, having inclined surfaces extending from its point to its inner and outer sides, the rise of the outer inclined surface being greater than that of the inner inclined surface. 110

HENRY C. SEARLE.
